UNITED STATES PATENT OFFICE.

WALTER S. CURTIS, OF WEST RANDOLPH, VERMONT.

DENTAL FLASK.

SPECIFICATION forming part of Letters Patent No. 374,585, dated December 13, 1887,

Application filed April 11, 1887. Serial No. 234,396. (No model.)

To all whom it may concern.

Be it known that I, WALTER S. CURTIS, of West Randolph, in the county of Orange and State of Vermont, have invented a new and useful Improvement in Dental Flasks; and I do hereby declare that the following is a full, clear, and exact description of the same, reference being had to the accompanying drawings, forming part of this specification.

10 This invention has reference to what are known as "dental flasks," and which are used for the purpose of uniting the artificial teeth to the artificial gum under pressure.

The invention consists in providing the 15 flask with two angular or wedge-shaped guides on opposite sides and projecting from and forming a part of the rim of the cope or upper part of the flask, and two corresponding slots on the rim of the nowel or lower part of 20 the flask, into which the guides pass and tightly fit when the two parts of the flask are forced together, and enabling the material in the upper part of the flask to unite naturally with that in the lower part of the flask, the 25 downward direction of the upper part of the flask in the process of uniting it with the lower part not being confined to any particular angle, as will be more fully set forth hereinafter.

30 In the drawings, Figure 1 is a side view of a dental flask united with the improved guides; Fig. 2, the two parts of a dental flask, showing a possible relative position when the process of uniting them is commenced; Fig. 3, 35 the same, showing another possible relative position. Fig. 4 illustrates the manner in which the flask may be opened or closed.

In the drawings, B is the lower part of the flask, in which the teeth are embedded in a 40 plaster mold to receive the gum.

A is the upper part of the flask, in which the plaster cast is secured preparatory to pressing the plastic base onto and around the teeth.

45 The gums are made of celluloid or other plastic material, and the teeth are secured by forcing the roots into the previously-prepared gums.

In the construction of a plastic upper plate 50 of teeth it is essential that the upper part of the flask pass downward more or less obliquely, varying according to the under-cut. By this improved method, the guides being free to move downward more or less obliquely, as the particular case in hand requires and as

is desired, the downward direction is governed by the lateral pressure, the lateral displacement of the gum will be uniform, and the plaster mold will not be broken or crumbled and mixed with the plastic gum, and as there 55 is no binding of the guides nor pressure of the gum on the edges of the plaster mold, much less pressure is required to bring the two parts of the flask together than by any method heretofore in use, and there is consequently much 60 less danger of displacing the teeth set in the plaster mold.

In the construction of a plastic under plate of teeth the downward direction of the upper 65 part of the flask is properly nearly vertical. By this improved method this vertical downward direction is accomplished with the same 70 desirable results as above described, as will be seen.

In separating a dental flask after forming a 75 plaster mold for an upper plate of teeth, it is essential that the rear of the top part of the flask be raised from its position first, and more rapidly than the front part, so as not to injure the portion of the mold forming the 80 under-cut. This is easily accomplished by this improved method, as the novel shape of the guides readily admits of the rear part being raised to any point desired while the two front portions of the flask remain together. This flask also readily admits of the 85 vertical upward direction required when separating the flask after the preparation of the mold for an under plate of teeth.

Having thus fully described my invention, 90 what I claim as new, and desire to secure by Letters Patent of the United States, is—

In a dental flask, and in combination, the upper part, A, having lugs projecting downward upon either side, the said lugs having 95 one of their sides extending vertically throughout their whole extent, and one side inclined from the lower end of the lug all the way to the edge of the said upper part, A, and lugs formed upon the lower part, said lugs having 100 inclined and vertical sides formed to correspond with the lugs of the upper part, all substantially as described.

In testimony whereof I have signed my name to this specification in the presence of two subscribing witnesses.

WALTER S. CURTIS.

Witnesses:

A. B. THOMAS,
W. H. NICHOLS.
